UNITED STATES PATENT OFFICE

WILLIAM EVENSEN, OF CHICAGO, ILLINOIS, ASSIGNOR TO GOSS PRINTING PRESS COMPANY, A CORPORATION OF ILLINOIS

PRINTING PRESS

Original application filed August 18, 1923, Serial No. 658,052. Divided and this application filed October 1, 1926. Serial No. 138,822.

The invention relates to printing presses and more particularly to the mechanism employed in rotary newspaper presses for displacing or equivalently indicating certain papers in the delivered stack, thereby to divide the stack or row of delivered papers into groups each of which contains a desired or predetermined number of papers.

This application is a division of my copending application Ser. No. 658,052 filed August 18, 1923.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, 20 constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a side elevation, with parts in section and with parts broken away, of a mechanism embodying the invention;

Fig. 2 is an end elevation, with parts in section, looking at Fig. 1 from the right;

Fig. 3 is a longitudinal, vertical section, 35 taken substantially on line 3—3 of Fig. 2;

Fig. 4 is a detached, fragmentary detail in horizontal section taken substantially on line 4—4 of Fig. 2; and

Fig. 5 is a side elevation of the delivery 40 mechanism of a rotary newspaper press with certain of the mechanism of the invention applied thereto, and showing certain mechanism which is also shown at the lower right hand part of Fig. 2.

In the delivery mechanism of rotary newspaper presses it is customary to have the mechanism designate or mark groups consisting of a predetermined number of newspapers in the delivered stack or row, the 45 designation being usually by displacing the

last paper of the desired number in the continuous row or stack upon the delivery belt.

The present invention is directed to providing means for nicely adjusting the flipper, forming a part of the designating or marking mechanism, whether or not the numbers of newspapers in the groups are varied or changed.

The present invention is also directed to providing means for varying the operation or periodicity of the designating or marking mechanism so as to indicate or mark groups of different numbers of newspapers as may be desired, and to provide for consequent and concomitant changes or variations in the operation of the various cooperating mechanism.

The usual construction for such a mechanism comprises in conjunction with the rotary fly of the folder, which lays the completed or folded newspapers in an even row or stack on the delivery belt, a flipper or swinging finger, operating in a definite time relation with the fly, and which periodically lifts or displaces a paper as it is delivered from the fly onto the belt so that it will project above the other papers in the row or stack on the delivery belt and so designate or mark a group containing a predetermined number of newspapers, the number being dependent on the time relation of the flipper finger to the rotary delivering fly.

The present invention is directed to nicely adjusting the flipper, whether or not the number of newspapers in the designated group is varied. The invention is also directed to changing the relation between flipper finger and the rotary fly so that the number of papers in the designated group may, if desired, be varied, and especially to thus vary the designated number in a relatively small degree, as say from twenty-five to twenty-six papers. The reference to a rotary fly and other details of the usual form of delivery must not be construed as limiting the invention, as it could be applied to other forms of delivery mechanism.

In connection with the foregoing, rectifying means are provided for maintaining to a nicety, or recovering, the proper relation be-

between the folder fly and the actuating cam, or equivalent actuating mechanism for the flipper finger. This nicety of adjustment is obtained whether or not the designating or marking mechanism is varied to change the count of the newspapers. When the gear drive is changed to effect the change in the number of papers in the group, the rectifying means will also insure proper relation between the folder fly and the actuating cam for the flipper finger as to secure the proper count or designation in conjunction with making the desired changes in counting mechanism

Other features and objects of the invention will be first set forth in connection with the appended detailed description of the present preferred embodiment and it will be understood that the foregoing general description and the following detailed description of the invention are illustrative and exemplary but are not restrictive of the invention.

Referring now to the embodiment of the invention, illustrated by way of example in the accompanying drawings and referring primarily to certain of the folding and delivery devices of a rotary printing press (Fig. 5), the rollers 1 and 2 of the transverse folder, which makes the final cross-fold in the newspaper, are journaled in the frame 3. A rotary fly 4 has its shaft 5 journaled in the frame 3, and is provided with a plurality of arms 6, between which are the spaces 7 into which the completed newspapers are dropped or delivered from the folding rollers 1 and 2.

The rotary fly 4 lays the completed papers upon a suitable delivery device, such as a traveling belt 8, running over a roller 9, and having supporting and tensioning rollers 10 and 11 carried, respectively, by arms 12 and 13, fixed to a shaft 14, journaled in the machine frame.

The finished papers are laid upon the belt 8 in a row or series uniformly spaced or disposed, and for the purpose of indicating, designating or marking groups containing a given number of papers, it is customary to periodically displace a paper in the series or rows upon the belt 8, the device effecting this operation after the delivery of the predetermined number of papers. Thus, each projecting paper will mark a group with a given number of papers therein between it and the next projecting paper. Thus the papers may be picked up and handled in exact numbers without counting.

In the mechanism for effecting this, a flipper arm 15 is adapted to operate periodically upon a folded paper in the rotary fly and give it a slight forward push or rather prevent its coming back in the fly as far as it otherwise would, just as it is delivered, for the purpose above described. The flipper arm 15 is fixed on an arm 16, which is fixed to a shaft 17, journaled in the machine frame 3. Fixed to shaft 17 is an arm 18, in the end

of which is journaled a cam roller 19, cooperating with a cam 20.

The mechanism so far described is of a usual or standard form, and it will be understood that the present invention may be applied to other forms of newspaper delivery devices than that herein exemplarily shown.

It is desirable to get a nicety of adjustment of the flipper without changing the count of the newspapers in any group.

It is also desirable frequently to change the number of papers in each marked or indicated group of the delivered papers, that is, to have the mechanism displace a newspaper after a given number have passed, or optionally or selectively, after a different given number of newspapers have passed.

It is further frequently desirable to vary the operation of the indicating means to change the number in the group relatively very little, for instance, to have the mechanism constructed and operated so as to mark or indicate either a group of twenty-five newspapers or twenty-six newspapers, although it will be understood that these numbers are merely illustrative.

Accordingly, means are provided for varying the period of operation of the flipper arm 15, said means being preferably arranged and located between the flipper arm and the drive therefor. For convenience, the detailed description of the present preferred embodiment will begin with the general driving mechanism and will end up at the flipper arm.

A driving gear 34 is fixed upon a shaft 35, journaled in the general frame 3. In the preferred embodiment a change gear, or speed change gear mechanism cooperates with the driving gear wheel 34, to change the period of operation of the flipper arm 15. A pinion 36 is shown in mesh with gear wheel 34, this gear wheel being fixed on a shaft 37 which is journaled in the end of the arm 38 of a bell crank lever 39, which bell crank lever is loosely pivoted by shaft 40, later to be described. Fixed also to shaft 37 to rotate with the pinion 36 is a pinion 41 which pinion is in mesh with a gear wheel 42 fixed on the shaft 40.

The alternative drive of the change gear, or speed changing gear, comprises a pinion 43, fixed to a shaft 44, and a pinion 45 is also fixed to shaft 44. This shaft is journaled in an arm 46, extending outwardly from the arm 47 of the bell crank lever 39. Pinion 45 is also in mesh with the gear wheel 42. The bell crank is provided with a handle 50, and with a bolt and slot holding device 51. Thus when the mechanism is in the position of Fig. 1, the drive from gear wheel 34 is through pinions 36 and 41 to the gear wheel 42. When the bell crank lever is rocked by moving handle 50 to the left, pinion 36 is thrown out of mesh with gear wheel 34, and pinion 43 is thrown into mesh with the gear wheel 34.

The ratios of the respective pinions are such that they will drive the gear wheel 42 at different speeds, so as to effect the desired difference in the period of operation of the flipper arm 15, and of its actuating cam 20 to effect the desired difference in counting the papers.

As embodied, the further driving connections to the flipper arm actuating cam 20 comprise means for rectifying or neutralizing the change caused in the relative position of the cam 20 and the folder fly 4, by shifting the change gear mechanism. This mechanism operates as stated to rectify the change in position between the cam and fly and thereby to get the proper count in the delivered newspapers.

In the embodied form, this rectifying means is applied to the driving connections to the cam 20 about to be described. Fixed on shaft 40 is a worm 58 (Figs. 2, 3 and 4) connected to the shaft by a spline 59, the worm accordingly rotating with the shaft but being slidably thereon. Means are provided for controlling the position of the worm along its shaft, the required movement being relatively very slight, to compensate for an opposite movement, caused by the operation of the change gear mechanism already described.

As embodied, a non-rotating washer 60 encircles the shaft, and abuts on the worm, the outer face 61 thereof being beveled. Abutting on the wedge-like washer 60 is a sliding, bifurcated wedge 62 beveled complementarily with washer 60. The shaft 40 passes through a central recess in the wedge, and the arms 63 and 64 of the wedge extend horizontally above and below the shaft. On its opposite face the wedge 62 bears against the frame 3.

Means are provided for moving the wedge 62 to and fro accurately and minutely with respect to the shaft 40, and as embodied, a screw shaft 68 is journaled in a bracket 69, carried upon the frame. The shaft has a hand wheel 70 at the exterior end thereof, with its hub abutting on the bracket 69, and with a positioning collar 71 fixed thereto on the other side of the hub, whereby the rod is rotatable in the journal bracket 69 but is held against longitudinal movement. At its other end, rod 68 is provided with a screw-thread 72, which is threaded into the tapped projection 73 of the wedge 62.

Thus as the hand wheel 70 is rotated, the wedge 62 is moved finely and accurately to and fro to correspondingly move the worm 58 along the shaft 40, thereby effecting a slight compensating or correctional relation between the worm and its worm wheel 80, later to be described. A helical spring 75 is in compression between the hub of the worm 58 and a collar 76, fixed on the shaft 40, and this spring yieldingly presses the worm against the washer 60.

Meshing with the worm 58 is a worm wheel 80, fixed on a shaft 81, which shaft is journaled in a bearing 82, carried on a bracket 83 supported by the machine frame, the hub of the worm wheel 80 abutting against one end of the bearing 82. A beveled gear wheel 85 is fixed to the other end of shaft 81, and has its hub abutting on the opposite end of the bearing 82.

Meshing with the beveled gear 85 is a beveled gear 86 rotatably mounted on a shaft 87 journaled in a supporting bearing and standard 88, fixed to the machine frame. Fixed to bevel gear 86 to rotate therewith is a gear wheel 92, which meshes with a gear wheel 93, rotatably carried on a shaft 94. Gear wheel 93 has its hub 95 integral with or fixed to the hub 96 of a part or member of the flipper arm actuating cam 20.

Thus when the hand wheel 70 is turned to move the adjusting or position-varying or controlling wedge 62, the worm 58 is moved longitudinally along its shaft 40, and by means of its movement it is possible to adjust the cam disc 20 to exact position.

Means are likewise provided for correspondingly setting the flipper finger or "kicker" and this is a very precise and delicate operation. In the embodied form of means for effecting this, the hub 96 of the cam 20 is keyed to the shaft 94, the hub carrying a circular flange 100. The cam 20 proper is circularly centrally recessed so that it will rest and also rotate upon the periphery of the circular flange 100. The flange 100 and the cam 20 are connected together to be angularly or circularly relatively positionable by suitable means, such as bolt and slot connections 102 passing through a slot in one and screwed into the other, and which may be of usual form.

In the embodied form of means for angularly positioning the rim 20 on the central part 100, as above referred to, there is rotatably mounted in the cam 20 a short shaft 106, to which is fixed a hand-wheel 107, on one face of the cam. Fixed also on shaft 106, and nested on the opposite face of the cam in alignment with the flange 100 is a pinion 108. A few gear teeth 109 are formed in the peripheral edge of the circular flange 100. By rotating the hand wheel 107, which is friction-tight, a very nice and precise positioning of the cam 20 with respect to its supporting hub 94 and the train of driving mechanism is secured.

The cam 20 is provided with one or more depressions 110, with which the cam roller 19 co-acts to actuate the kicker arm or flipper 15. If desired, a silencing plate 112 may be provided for the depression 111, and thereby the number of designated papers may be doubled. The plate 112 is pivotally supported at 113 and has an arcuate bolt and slot connection 114, with the cam 20 whereby it may be

held in either the operative or inoperative position.

It will be clear from the foregoing that the resultant displacement of the flipper, due to changing the count of the newspapers in any group, may be corrected or compensated by sliding the worm gear 58 along its shaft by actuating the wedge 62 through the hand wheel 70 and cooperating screw-threads.

10 Or, the same correction or compensation can be secured by adjusting the cam 20 upon the member 100. In the latter case, the worm gear adjustment would not be necessary.

15 It will be further noted that the adjustment of the worm gear 58 can be made while the press is running. This is also true in those cases where it is desired to make the adjustment simply by means of the adjustable cam, for the cam moves so slowly that 20 the parts can be readily adjusted while the press is in motion. It will also be noted from the foregoing description that the flipper adjustment can be made by the adjustable cam simply to insure a nicety of adjustment of the flipper, without any dependence whatever on or connection with the counting mechanism controlling the number 25 of newspapers in the groups. Or, the sliding worm gear 58 controlled by the wedge 62 30 could be used for the same purpose, even if gears are not used to change the count.

When the gears are used to change the count, the position of the flipper is adjusted or rectified by either the sliding worm 58 35 and its operating connections, or by the adjustable cam 20. Either mechanism is sufficient to make the adjustment. Such an adjustment or rectification is necessitated by the fact that when the gears 36, 43 are shifted 40 to change the count, shaft 40 is angularly shifted, which angular shift would be transmitted through gears 80, 85, 86, etc. to cam 20, and would introduce an error in the count, unless compensated for by either of the two 45 described rectifying or adjusting devices.

The invention in its broader aspects is not limited to the specific mechanisms shown and described but departures may be made therefrom within the scope of the accompanying 50 claims without departing from the principles of the invention and without sacrificing its chief advantages.

What I claim is:—

1. A newspaper counting mechanism including in combination a rotary fly, a flipper finger for displacing a newspaper to mark a group of a predetermined number, a shaft, a hub having a circular flange keyed to the shaft, a cam supported on the circular flange and adapted to move with relation to it, and means to adjust the cam in any desired position on the circular flange.

2. A newspaper counting mechanism including in combination a rotary fly, a flipper finger for displacing a newspaper to mark a

group of a predetermined number, a shaft, a hub having a circular flange keyed to the shaft, a flipper finger actuating cam supported on the circular flange and adapted to move with relation to it, a stub shaft relatively mounted in the cam, a hand wheel on the stub shaft, a pin mounted on the shaft, and gear teeth mounted on the circular flange.

3. A newspaper counting mechanism including in combination a flipper for designating a newspaper to indicate a group consisting of a predetermined number of papers, a flipper actuating cam continuously driven and means for varying the time of actuation of the flipper including a rotating rack and pinion associated with the cam.

In testimony whereof I have signed my name to this specification.
